UNITED STATES PATENT OFFICE.

JAMES W. GAFFEY, OF CEDAR RAPIDS, IOWA.

REFRACTOMETER.

Application filed July 16, 1921. Serial No. 485,187.

To all whom it may concern:

Be it known that I, JAMES W. GAFFEY, a citizen of the United States, residing at Cedar Rapids, in the county of Linn and State of Iowa, have invented new and useful Improvements in Refractometers, of which the following is a specification.

This invention relates to refractometers or eye testing devices and has for an object the provision of a device by means of which a single line of type or indicia may be singly and selectively exposed in a clear and distinct manner.

Another object of the invention is the provision of a device of the above character which may be operated from a remote point, by means of a single operating cord which is arranged to perform a number of separate functions, thus simplifying the operation of the device.

With the above and other objects in view, the invention further includes the following novel features and details of construction, to be hereinafter more fully described, illustrated in the accompanying drawings and pointed out in the appended claims.

In the drawings:

Figure 1 is a front elevation of the device showing the characters or indicia exposed through the upper sight opening.

Figure 2 is a similar view showing the characters or indicia exposed through the lower sight opening.

Figure 3 is a view illustrating the use of the device for testing color blindness.

Figure 4 is a vertical transverse sectional view,

Figure 5 is a rear elevation with the back of the casing removed,

Figure 6 is a view of the indicia carrying disk.

Figure 7 is a like view of the cover disk.

Figure 8 is a horizontal section through the device.

Referring in detail to the drawings, wherein like characters of reference denote corresponding parts, the reference character 10 indicates a casing which is shown as of rectangular shape and includes a front wall 11 and a rear removable wall 12, the latter being preferably provided with marginal flanges 13 for engagement within the casing so as to provide a neat and compact appearance.

Formed within the front 11 of the casing is an upper sight opening 14 and a lower

sight opening 15, the former being surrounded by an inwardly extending flange 16, while the flange 17 which surrounds the lower opening extends both within and without the casing.

Extending transversely through the casing is a rod or bolt 19 which forms a shaft for a pair of rotatably mounted disks, to be later described in detail. In addition, this shaft provides means for removably holding the rear wall 12 of the casing in position.

Mounted upon the shaft 19 is a disk 20, preferably formed of glass, the said disk having its rear face covered with a suitable translucent material 21, being provided with a hub 22.

The disk is provided upon its opposite face with letters or suitable indicia which is adapted to be brought within either of the sight openings and for this purpose there is provided an operating arm 23 which is mounted for pivotal movement upon the shaft 19.

A sleeve or bushing 24 is preferably interposed between the opening provided in the arm 23 and the shaft 19 and is of a length to extend through an opening provided in the rear wall 12 of the casing.

Carried by the arm 23 is a pivotally mounted dog 24' which is arranged to engage notches disposed transversely around the hub 22 so that when the arm is moved upward the dog will engage one of these notches to rotate the disk 20.

The arm is normally held in lowered position by a spring 26, which has one end secured to the arm and its opposite end secured to an arm 27, which is pivotally mounted as shown at 28 within the casing.

The upper end of this arm 27 carries a brake shoe 29 which engages the periphery of the hub 22 so that the disk 20 will be held stationary until movement is imparted thereto through the operation of the arm 23.

In order to operate this arm, the dog 24 has attached to one end a cord or cable 30 which passes through an opening provided in the top of the casing 10 and may extend to any convenient point.

Also mounted upon the shaft 19 is a second disk 31, which is provided with openings 32 and 33.

These openings are adapted to be brought into register with the openings 14 and 15 respectively provided in the front of the casing 10 and when so positioned will expose certain of the indicia upon the disk 20 to view.

In addition, the disk 31 is provided with spaced openings 34 which are covered by a translucent covering of dif-

ferent colors and are so arranged within the disk 31 as to be exposed through the sight opening 15.

In order to rotate the disk 31 it is provided upon its rear face with spaced teeth 35 which are adapted to be engaged by a spring dog 36 mounted upon the outer end of the arm 23, so that in addition to operating the disk 20, operation of the arm 10 will rotate the disk 31. The disk 20 may be rotated independently of the disk 31 by limiting the pivotal movement of the arm 34, as the dog 24 is located between the dog 36 and the pivotal mounting of the arm and 15 the grooves 25 of the hub 22 are relatively close, the said disk 21 may be rotated by a relatively slight movement of the arm. Thus, the disk 31 may be rotated to bring either of its openings into proper position 20 and the disk 20 may be rotated to bring the desired indicia into view through these openings.

In order to yieldingly hold the disk 31 stationary, the said disk is provided with a 25 hub 37 having spaced notches 38, which are adapted to be engaged by a spring dog 39 which is pivotally mounted within the casing 10. The casing is further provided with a stop 40 which limits the downward movement 30 of the arm 23 and also acts as a guide for the disk 20.

Carried by the removable wall 12 of the casing 10 are brackets 41, which carry light 35 sockets 42, the latter being adapted to contain incandescent lamps to supply proper illumination at the rear of the disks, the said lamps being located adjacent the openings 14 and 15. A conductor 43 extends from the lamp sockets to the outside of the casing for 40 connection with a suitable source of current. The disks 20 and 31 are preferably separated by a small disk 44, suitable washers being interposed between the disks.

The invention is susceptible of various 45 changes in its form, proportions and minor details of construction and the right is herein reserved to make such changes as properly fall within the scope of the appended claims.

Having described the invention what is 50 claimed is:—

1. An eye testing device comprising a casing having spaced sight openings therein, a disk mounted for rotation within the casing and having indicia thereon, a cover 55 disk mounted for rotation within the casing between the indicia carrying disk and the

casing opening, said cover disk also having spaced openings therein adapted to be singly brought into register with the openings of the casing and means common to both disks, 60 whereby the indicia carrying disk may be independently rotated to selectively position the indicia within the openings, or both the disks simultaneously rotated.

2. An eye testing device comprising a 65 casing having spaced sight openings therein, a disk mounted for rotation within the casing and having indicia thereon, a cover disk also mounted for rotation within the casing between the indicia carrying disk and the 70 casing openings, a pivotally mounted arm for controlling the disks, a dog secured to the arm and engageable with the indicia carrying disk to rotate the latter, a second dog also carried by the arm and engageable 75 with the cover disk to rotate the latter and means for operating the arm.

3. An eye testing device comprising a casing having spaced sight openings therein, 80 a disk mounted for rotation within the casing and having indicia thereon, a cover disk also mounted for rotation within the casing between the indicia carrying disk and the casing openings, a pivotally mounted arm for controlling the disks, a dog secured to 85 the arm and engageable with the indicia carrying disk to rotate the latter, a second dog also carried by the arm and engageable with the cover disk to rotate the latter and a cord secured to the first mentioned disk for 90 operating the arm.

4. An eye testing device comprising a casing having spaced sight openings therein, 95 a disk mounted for rotation within the casing and having indicia thereon, means including a pivotally mounted arm whereby the disk may be rotated to selectively position the indicia within the openings, a cover disk mounted for rotation within the casing between the indicia carrying disk and the 100 casing opening, said cover disk also having spaced openings therein adapted to be singly brought into register with the openings of the casing, means engageable by the pivotally mounted arm whereby the cover disk may 105 be operated, a pivotally mounted brake shoe for holding the indicia carried disk in position and a spring connecting the pivotal mounting of the brake shoe and a pivotally mounted arm.

In testimony whereof I affix my signature.
JAMES W. GAFFEY.
